CLAIM

The ornamental design for a laundry basket with 3 section laundry sorters, as shown and described.

DESCRIPTION

FIG. 1 is a top, front and right side perspective view of a laundry basket with 3 section laundry sorters, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front and left side perspective view of the laundry basket;

FIG. 10 is a top, front and right side perspective view of 3 section laundry sorters inside the laundry basket; and,

FIG. 11 is an enlarged view of the portion labeled “11” framed in FIG. 1.

The dot dash-lines shown on the laundry basket with 3 section laundry sorters depict stitching that form no part of the claimed design. In FIG. 1 and FIG. 11, a broken line rectangular frame defines the boundary of an enlarged view and form no part of the claimed design.
